PREFORMED STEP STRUCTURE

Wilbert R. Wale, Toledo, Ohio

Application June 29, 1944, Serial No. 542,712

5 Claims.

(Cl. 72—96)

My invention relates to improvements in steps, especially, although not necessarily, door steps, the primary object in view being to provide inexpensive, easily constructed steps of preformed slabs, or beams, together with means for permanently and rigidly connecting the slabs together so as to form a substantially indestructible assembly which is proof against sagging, or settling, throughout the same, and in which the connecting means is hidden from view.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in side elevation of a preformed step structure constructed in accordance with my invention, in its preferred embodiment,

Figure 2 is a view in horizontal section taken on the line 2—2 of Figure 1,

Figure 3 is a view in vertical section taken on the line 3—3 of Figure 2,

Figure 4 is a view in vertical section taken on the line 4—4 of Figure 2 and drawn to an enlarged scale,

Figure 5 is a view in perspective of one of the wall slabs.

Figure 6 is a view similar to Figure 2 of a modified form of the invention.

Referring to the drawings by numerals, and first to Figures 1 to 5, my improved step structure, in its preferred embodiment, comprises a pair of side walls 1 each embodying superposed slabs, or beams, 2 arranged in superposed relation with the front ends of successively higher slabs 2 set back from the front ends of the lower slabs to support the treads, presently described. The slabs 2 are preformed of molded concrete each with a vertical central notch 2' in the front end thereof, the sides of which converge forwardly, as best shown in Figure 2. Adjacent the rear ends of the walls 1, each slab 2 is formed with a vertical through bore 3 therein, the bores 3 of the slabs 2 of each side wall being vertically aligned, as shown in Figure 3. A single cylindrical key 4 with a central core 5 in the form of a metal rod extends through the bores 3 of the slabs 2 of each side wall 1 to connect said slabs together at the rear end of the wall. The keys 4 are formed of poured concrete introduced into the bores 3 around the core 5.

The risers 6 are preferably formed of a pair of

preformed concrete slabs 7 of similar length arranged to form a butt joint 8 in the longitudinal center of the stair structure and with outer ends fitting against the front ends of the slabs 2 of the side walls 1. Each slab 7 is provided in its rear side and adjacent its outer end with a notch 7' similar to the notch 2' in the adjacent slab 2 and mating with the notch 2' with its side walls converging rearwardly. At their inner ends the slabs 10 1 of each riser 6 are formed with a pair of vertical mating notches similar to the notches 2', 7', and designated 9.

Poured concrete keys 10 in the notches 2', 7' secure the outer ends of the slabs 1 of each riser 15 6 to the front ends of the appropriate slabs 2 of the side walls 1. Similar keys 11 in each pair of notches 9 secure the slabs 7 of each riser 6 together. The keys 10, 11 may be reinforced by upright rods, as at 12 and by crimped strip reinforcement of suitable metal, as at 13.

The treads 14 are preferably formed of single preformed concrete slabs supported by the front ends of the slabs 2 and the risers 6. Each tread 14 is provided with right angled key rods 15 having one end embedded in the tread and the other end depending from the tread, said key rods 15 having the depending ends thereof embedded in the keys 10, 11 which, it will be understood, is accomplished by inserting said ends of the key rods 15 in said keys 10, 11 before the latter are set.

In case a center wall is desired in the step structure, said wall is formed in substantially the same manner as the side walls 2 with a notch 16 in the front end of each slab 17, as shown in Figure 6. The inner ends of the slabs 18 of the risers 19 are provided with a pair of right angled vertical notches 20 similar to the pair of notches 9 but forming with the notch 16 a cruciform notch arrangement, as shown in Figure 6, for containing a transversely cruciform poured concrete key 21 reinforced in the same manner as previously described with reference to the notches 2', 7' and 9.

The manner in which the described component parts of my improved step structure are assembled will be readily understood. The side walls 1 and the center wall, if such be required, are built up and the keys 4 then poured into the bores 3. The risers 6 and 19, as the case may be, are then properly located and the keys 10, 11, 21 poured in. The treads 14 are next secured in proper position with the rods 15 embedded in the keys 10, 11 and 21, as will be understood.

The foregoing will, it is believed, suffice to im-

part a clear understanding of my invention without further explanation.

Manifestly, the invention, as described, is susceptible of modification without departing from the inventive concept, and right is herein reserved to such modifications as fall within the scope of the appended claims.

What I claim is:

1. A step structure comprising elongated superposed wall-forming members having front and rear ends, the front ends of successively higher members being stepped back from the front ends of lower members, a vertical single key connecting the rear ends of the members of each said wall, risers extending across said front ends of the members, keys extending from the risers into said front ends of said members, treads overlying said front ends of said members and said risers, and keys depending from said treads into the second-mentioned keys, said members, risers and treads comprising preformed concrete slabs.

2. A step structure comprising elongated superposed wall-forming members having front and rear ends, the front ends of successively higher members being stepped back from the front ends of lower members, a vertical single key connecting the rear ends of the members of each said wall, risers extending across said front ends of the members, keys extending from the risers into said front ends of said members, treads overlying said front ends of said members and said risers, and keys depending from said treads into the second-mentioned keys, said members, risers and treads comprising preformed concrete slabs, said risers comprising pairs of slabs arranged with ends abutting, and keys connecting the abutting ends of said pairs together.

3. A step structure comprising elongated superposed wall-forming members having front and rear ends, the front ends of successively higher members being stepped back from the front ends of lower members, a vertical single key connect-

ing the rear ends of the members of each said wall, risers extending across said front ends of the members, keys extending from the risers into said front ends of said members, treads overlying said front ends of said members and said risers, and keys depending from said treads into the second-mentioned keys, said members, risers and treads comprising preformed concrete slabs, the second-mentioned keys flaring inwardly of the risers and members.

4. A step structure comprising elongated superposed wall-forming members having front and rear ends, the front ends of successively higher members being stepped back from the front ends of lower members, a vertical single key connecting the rear ends of the members of each said wall, risers extending across said front ends of the members, keys extending from the risers into said front ends of said members, treads overlying said front ends of said members and said risers, and keys depending from said treads into the second-mentioned keys, said members, risers and treads comprising preformed concrete slabs, the second-mentioned keys being formed of poured concrete.

5. A step structure comprising elongated superposed wall-forming members having front and rear ends, the front ends of successively higher members being stepped back from the front ends of lower members, a vertical single key connecting the rear ends of the members of each said wall, risers extending across said front ends of the members, keys extending from the risers into said front ends of said members, treads overlying said front ends of said members and said risers, and keys depending from said treads into the second-mentioned keys, said members, risers and treads comprising preformed concrete slabs, said depending keys comprising metal rods embedded at one end in said treads.

WILBERT R. WALE.
